UNITED STATES PATENT OFFICE

ALFRED W. ABRAHAMSEN AND ANDERS SKARSTEN, OF QUEENS VILLAGE, NEW YORK

FLOOR SCRAPER

Application filed January 25, 1929. Serial No. 334,963.

This invention relates to wood scrapers, more particularly floor scrapers, adapted for use on wood and parquet floors, the object of the invention being to provide an improved 5 floor scraper simple in construction, inexpensive to manufacture and durable in use, the present invention being an improvement upon that shown and described in Abraham- 10 sen Patent No. 1,670,646 of May 22, 1928.

10 In the drawings accompanying and forming part of this specification, Fig. 1 is a side partly sectional view of this improved floor 15 scraper;

Fig. 2 is a bottom view thereof, and 15 Fig. 3 is a detail partly sectional view, enlarged, of the front part of the scraper.

Similar characters of reference indicate 20 corresponding parts in the several views.

Before explaining in detail the present improvement and mode of operation thereof, we 25 desire to have it understood that the invention is not limited to the details of construction and arrangement of parts which are illustrated in the accompanying drawings, 30 since the invention is capable of other embodiments, and that the phraseology which we employ is for the purpose of description and not of limitation.

The primary object of the present improvement is the provision in such a scraper of improved means for holding the blade and means for insuring the proper filing or sharpening of the cutting edge or cutter. In 35 the Abrahamsen patent above referred to, the blade 3 was carried by some suitable handle 2, the blade and the cutter 4 having a detachable connection whereby the cutter could be readily renewed. In the present improvement, the handle 2 carrying the blade 3 comprises a suitable block preferably wood, formed at its front end to provide an overhanging portion 5 and slotted as at 6 rearwardly thereof. This overhang 5 thus supports the blade at the rear face thereof when 40 in use. The blade is provided with a bent

inner edge 7 so that when blade is forced sidewise into the slot 6 of the block this bent edge will cut a groove in the block and thus hold the blade in position. The blade is provided with a detachable, interlocked cutter 50 similar to that shown and described in the patent above referred to.

The wood block handle is provided at its under side with an opening 8 for the reception of a detachable handle 9 having a 55 threaded ferrule 10 at its end adapted to be turned into a threaded socket 11 secured to the block. This block is of suitable shape so that it can be readily grasped in the hand whereby the scraper may be used for fine 60 work. When however, fast or rough scraping is desired, the detachable handle 9, hereinafter referred to, may be attached to the block.

For the purpose of insuring the proper filing or sharpening of the blade, we have provided a suitable pivoted support or guide and for this purpose a V-shaped channel piece 12 is provided at the top or back side of the blade, this channel piece being fastened to 65 the under side of the overhanging nose 5 of the block, the forward edge of this V-shaped channel piece resting on top of the blade. Secured in this V-shaped channel or hinge piece for shiftable or swinging movement is 70 a filing guide 13, this guide comprising a curved member, having a pair of inwardly projecting portions 15 extending into the V-shaped channel piece with the inner edge of the curved member in position to engage the 75 blade 3 whereby the spring of the blade will hold the swinging member in either its guiding position or non-usable position, in other words, in either of its adjusted positions. When it is desired to sharpen the edge of the 80 cutter, the blade is swung down away from the nose of the block so that it is in position to support and guide the file 16, see Fig. 3, used for sharpening the cutter, thus giving the file two points of support, one on the cut- 85 90

ter edge and the other along the curved side of the guide thereby insuring the proper sharpening of the cutter in an expeditious manner.

5. When the guide 13 is not in use, it is shifted into a different position as, for instance, over the curved nose of the block where it is out of the way.

It is to be understood that by describing in detail herein any particular form, structure or arrangement, it is not intended to limit the invention beyond the terms of the several claims or the requirements of the prior art.

Having thus explained the nature of our said invention and described a way of constructing and using the same, although without attempting to set forth all of the forms in which it may be made, or all of the modes of its use, we claim:

20. 1. A floor scraper comprising a handle having a blade provided with a cutting edge, and means permanently carried by one of said parts for guiding a sharpening instrumentality for the cutting edge.

25. 2. A floor scraper comprising a handle having a blade provided with a cutting edge, and means carried by one of said parts and swingable from an inoperative to an operative position for guiding a sharpening instrumentality for the cutting edge.

30. 3. A floor scraper comprising a handle having a blade provided with a cutting edge, and means carried by one of said parts for shiftable movement from an inoperative to an operative position for guiding a sharpening instrumentality for the cutting edge.

40. 4. A floor scraper comprising a handle having a blade provided with a cutting edge, and means carried by the handle and shiftable into position relatively to the cutting edge for guiding a sharpening instrumentality for the cutting edge, whereby said means in one position is away from the cutting edge.

45. 5. A floor scraper comprising a handle having a blade provided with a cutting edge, and means shiftable relatively to the handle and blade for guiding a sharpening instrumentality for the cutting edge, whereby in one position it is away from the cutting edge and in another position adjacent thereto.

55. 6. A floor scraper comprising a handle, a blade carried thereby having a cutting edge, and a shiftable spring-controlled guide carried by one of said parts for guiding a sharpening device and so located that the spring of the blade will maintain the guiding device in its several adjusted positions.

60. 7. A floor scraper comprising a slotted block having a forwardly projecting nose, a blade carried thereby and constructed to receive a detachable cutter, and shiftable means carried by the block and co-operating with the blade and shiftable into position to guide a sharpening device for sharp-

ening the cutter and also shiftable into position over the nose of the block when not in use.

8. A floor scraper comprising a handle, a blade carried thereby having a cutting edge, and a shiftable permanently carried guide co-operating with the handle and blade whereby it is held in one position for guiding a sharpening device and in another position when not in use. 75

9. A floor scraper comprising a block formed handle, a blade carried thereby, a detachable cutter carried by the blade, and a shiftable guide located at the forward end of the block and shiftable into juxtaposition with the blade for guiding a sharpening device and shiftable away from the blade and over the end of the block when not in use. 80

10. A floor scraper comprising a block formed handle, a cutter projecting from the forward end of the block, and a guide pivotally mounted at the forward end of the block and co-operating with the blade for guiding a sharpening device and shiftable to a position over the end of the block when not in use. 90

11. A floor scraper comprising a handle having a forwardly projecting nose, said nose supporting a scraping member, and guiding means shifted into juxtaposition with the blade for guiding a sharpening device for the scraping member and shiftable away from the scraping member when not in use. 95

12. A floor scraper comprising a handle having a forwardly projecting curved nose, a blade carried thereby and provided with a cutting edge and a shiftably-mounted curved guiding device located at the end of the nose and shiftable into position over the curved nose or into position in juxtaposition to the cutting edge to guide a sharpening device to the cutter. 100

13. A floor scraper comprising a handle, a blade carried thereby provided with a cutter, and a shiftably supported guiding device shiftable into position over the end of the handle block or into position to guide a sharpening device to the cutter. 110

14. A floor scraper comprising a handle, a blade carried thereby provided with a cutter, and a shiftably-mounted spring-controlled guiding device shiftable into position over the end of the handle block or into position to guide a sharpening device to the cutter and comprising a curved member having a part in position to co-operate with the blade, the spring control acting to maintain the guide in either of its adjusted positions. 115

15. A floor scraper comprising a handle and a scraping member and a sharpening guide carried by the scraper and forming a rest for guiding the sharpening member thereby to insure the sharpening of the scraping member at the proper angle. 125

16. A floor scraper comprising a handle and a scraping member and a shiftable sharpening guide located in position and forming a rest for the sharpening member thereby to insure the sharpening of the scraping member at the proper angle and shiftable away from the scraping member when not in use.
